UNITED STATES PATENT OFFICE.

MARGARET A. SELSOR, OF NEW YORK, N. Y.

DESIGN FOR TROUSERS.

52,470.

Specification for Design. Patented Sept. 24, 1918.

Application filed February 18, 1918. Serial No. 218,003. Term of patent 14 years.

To all whom it may concern:

Be it known that I, MARGARET A. SELSOR, a citizen of the United States, and a resident of the city, county, and State of New York, have invented a certain new, original, and ornamental Design for Trousers, of which the following is a specification, reference being had to the accompanying drawing, forming part thereof, in which—

Fig. 2 is a side elevation of the same.

I claim:

The ornamental design for trousers, as shown.

MARGARET A. SELSOR.
